UNITED STATES PATENT OFFICE.

WILLIAM SIDNEY WHYTE, OF BEDFORD, INDIANA.

PNEUMATIC CHISEL.

1,334,686.

Specification of Letters Patent. Patented Mar. 23, 1920.

Application filed July 23, 1919. Serial No. 312,710.

To all whom it may concern:

Be it known that I, WILLIAM SIDNEY WHYTE, a citizen of the United States, residing at Bedford, in the county of Lawrence and State of Indiana, have invented new and useful Improvements in Pneumatic Chisels, of which the following is a specification.

This invention relates to pneumatic tools, particularly to chisels, and has for its object the provision of a handle member associated with a pneumatically operated chisel which is so constructed as to absorb the shocks and jars incident to the use of the tool and prevent injury to the hands of the operator.

An important object is the provision of a handle member of this character formed as a casing within which is slideable the chisel member, the chisel member and casing being provided with coöperating guide members, and the casing carrying spring members having their ends engaging within notches in the chisel member whereby to provide resilience for absorbing shock.

An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a side elevation of my device associated with a pneumatic hammer,

Fig. 2 is a central longitudinal sectional view through my device, the chisel member being in elevation,

Fig. 3 is a cross sectional view on the line 3—3 of Fig. 2,

Fig. 4 is a fragmentary side elevation of the chisel member, showing one of the guide members therein,

Fig. 5 is a fragmentary side elevation of the chisel member, showing one of the spring engaging notches therein, and

Fig. 6 is a side elevation of a chisel member of somewhat modified form.

Referring more particularly to the drawings, the letter A designates a pneumatic hammer of ordinary type with which is connected the usual air hose B. The internal mechanism of the hammer A is not shown as it may be any one of several well

known types and is not essential to an understanding of this invention.

In carrying out my invention I provide a handle member formed as a casing including similar sections 10 which are elongated and which are of any preferred cross sectional configuration. Disposed within these sections 10 are longitudinally extending guide members 11 in the nature of bars 65 formed rectangular in cross section, and arranged in spaced relation. Disposed upon the sides of the sections 10 and covering the space between them are leaf spring members 12 which are secured in place by means 70 of screws 13 which pass through the spring members, through the sections 10, and into the guide bars 11. These screws consequently not only hold the spring members 12 in position but also hold the guide bars 75 in position within the handle casing. At one end of the casing the ends of the springs 12 are bent outwardly and then inwardly toward the center of the casing, as shown at 14, and these ends of the springs are thinned 80 toward their free extremities, as shown at 15, for a purpose to be described.

The chisel member is designated by the numeral 16 and is formed as a bar preferably rectangular in cross section throughout 85 the major portion of its length and provided at one end with a cylindrical extension 17 adapted for disposition within the pneumatic hammer A to be engaged by the plunger, not shown, therein. At its other end, 90 the chisel member carries an enlarged head 18 having a cutting edge 19 and the particular contour or formation of this head will depend entirely upon the use to which the chisel is to be put. Adjacent the cylindrical extension 17 the opposite sides of the chisel have formed therein notches 20 within which are engaged the thinned free ends 15 of the spring 12.

In order that the chisel will be properly 100 guided in its movement within the handle casing, I provide a plurality of plug like members 21 which extend transversely through the chisel body, which are cylindrical in shape within the chisel body, and 105 which have their projecting ends 22 flattened upon opposite sides, as shown at 23.

When the parts of the device are assembled the projecting ends 22 of the plug members 21 are engaged between the spaced 110 guide bars 11 at each side of the casing and the chisel body is slideable between the guide

bars at opposite side of the casing, as clearly shown in Fig. 3.

In the use of the tool it will be seen that when the operator holds the casing 10 in his hand and permits operation of the pneumatic hammer, the chisel 16 will be given the proper blows for performing its cutting action. Owing to the fact that the ends 15 of the spring members are gradually reduced in thickness, these ends will be very resilient and will give as the chisel is struck so as to permit the necessary longitudinal movement of the chisel while still remaining in engagement within the notches 20. Any lateral movement of the chisel is of course prevented, owing to the engagement of the chisel body between the opposite guide bars and the engagement of the extensions 22 between the guide bars. From this construction it will be seen that the shock resulting from holding the chisel directly in the hand will be entirely avoided and that the tool may be used with comfort and without any danger whatever.

It is of course understood that many changes or variations may be resorted to without departing from the spirit of the invention, as for example, instead of providing the plug members 21 extending through the chisel, I may brace the sides of the chisel to provide integrally formed lateral extensions 24, as shown in Fig. 6, these extensions being the equivalent of the extensions 22 on the plugs 21.

It will be observed that when desired, the chisel may be removed by pulling it longitudinally sharply to draw the notches 20 out of engagement with the spring tongues 15. It will be noted that the construction is simple and that the device is consequently not liable to derangement.

Having thus described my invention, I claim:—

1. A device of the character described comprising a casing serving as a handle and formed of two separate sections of elongated form arranged in spaced relation, spaced guide bars disposed within said sections, leaf springs disposed upon the sides of said sections and covering the spaces therebetween, securing members passing through said springs, through the walls of said sections, and into said guide bars, said springs at one end being bent outwardly and then inwardly 55 toward the center of said casing and being

gradually reduced in thickness to define spring fingers, said fingers extending through the spaces between said sections, a chisel member formed as a bar rectangular in cross section disposed within said casing 60 with opposite sides engaging against said guide bars, one end of said chisel member having a head provided with a cutting edge and the other end being formed as a reduced cylindrical extension adapted for insertion 65 within the casing of a pneumatic hammer, a plurality of plug members extending laterally through and projecting beyond the sides of said chisel member, said plug members being cylindrical in shape in said chisel 70 member and their projecting ends being flattened upon opposite sides and slidably engaged between said guide bars, said chisel member being provided in opposite sides with notches engaged by the inner ends of 75 said spring members.

2. A device of the character described comprising a handle formed as a casing, pairs of guide bars secured within said casing and arranged in spaced relation, strips 80 secured upon the sides of said casing, and terminating at one end in spring tongues extending into said casing, a chisel member formed as a bar having one end provided with a cutting edge and its other end formed 85 as a cylindrical extension adapted for engagement within a pneumatic hammer, said chisel member being disposed within said casing in engagement with said guide bars, and a plurality of members extending laterally through said chisel member, projecting 90 beyond the sides thereof and slidably engaged between said pairs of guide bars, said chisel member being provided in opposite sides with notches engaged by said spring 95 fingers.

3. A device of the character described comprising a casing constituting a handle, spring fingers at one end of said casing extending thereinto, guide members within 100 said casing, a chisel member slidable within said casing and having one end provided with a cutting edge and its other end adapted for engagement within a pneumatic hammer, lateral projections on the sides of 105 said chisel member engaging said guide members and said chisel member being provided with notches engaged by said spring fingers.

WILLIAM SIDNEY WHYTE.
